AUGUST B. VOGES AND ANTHONY VOGES, OF CINCINNATI, OHIO.

PUMP.

1,398,408.

Specification of Letters Patent. Patented Nov. 29, 1921.

Application filed December 9, 1920. Serial No. 429,396.

To all whom it may concern:

Be it known that we, AUGUST B. VOGES and ANTHONY VOGES, citizens of the United States, residing at Cincinnati, in the county 5 of Hamilton and State of Ohio, have invented certain new and useful Improvements in Pumps, of which the following is a specification.

Our invention relates to pumps, and more 10 especially to pneumatic-tire pumps. Its object is to provide for either single or double action of the pump, in a simple manner; and in general to simplify the construction of pumps of this character, especially in the inlet and outlet valves thereof. Other objects 15 will appear in the course of the ensuing description.

We attain these objects by the device illustrated, for example, in the accompanying 20 drawing, in which—

Figure 1 is a sectional front elevation of the pump, the lower part being in section on a vertical plane on the pump center line;

Fig. 2 is a sectional side elevation of the 25 pump, the lower part being in section on a vertical plane at right angles to that of Fig. 1, on the center line, and the upper part of the pump also being partly in section in the same plane as that of the bottom section in 30 this view;

Fig. 3 is a partial plan view, enlarged, 35 with the handle and its fastenings omitted, showing the upper inlet-valve construction; with the parts in position for double action of the pump;

Fig. 4 is a similar view, with the parts in position for single action;

Fig. 5 is a partial vertical section of upper parts of the pump, on a plane corresponding to the line 5—5 of Fig. 4; and 40

Fig. 6 is a detail perspective view of the upper inlet-valve assembly, part of the handle being omitted.

The base 1 comprises the hub 2 flanked by 45 foot-plates 3, preferably corrugated as indicated. The hub 2 lies entirely above the bottom surfaces of the foot-plates, with a bottom cavity 4 and a top cavity 5, separated by the partition 6 across the hub, which thus 50 forms the lower head of the pump cylinder, the shell 7 of which has its lower end screwed into the top cavity 5 of the base hub.

The lower-inlet valve comprises the disk 8 with a depending stem 9 at the center of

its lower side, and preferably with a boss 10 centrally of its top, reinforcing the disk and stem junction. A washer 11 has a central opening through which the stem 9 extends down, with the washer 11 close against the under face of the disk 8, to which it may be held either merely by the tightness of fit of the stem 9 in its opening, or by cementing or other additional fastening. The partition 6 of the base hub has the central hole 12, through which the valve-stem 9 slidingly extends; and a pin 13 passes through the lower end part of the stem 9, far enough down to permit the disk 8 and its washer 11 to rise some distance from the upper face of the partition 6, but not to escape entirely therefrom. At opposite sides of the stem-receiving hole 12, the partition 6 has inlet holes or ports 14, closed by the washer 11 when the latter is against the upper face of the partition 6, but opened as the washer 11 rises. As shown, the cylinder-shell 7 does not reach to the bottom of the cavity 5; and the disk 8 and washer 11 are of considerably less diameter than the cavity, so that they have ample room for the slight up and down movement required.

At the front, the base hub 2 has a tapped opening through its wall, into this space left between the bottom of the shell 7 and bottom of the cavity 5. The lower outlet valve comprises the nipple 15 screwed into the tapped base opening, with an enlargement 16 forming a shoulder confining a gasket 17 against the outside of the wall around the tapped opening. The other end part of this nipple 15 is a smooth extension 18 with the enlargement 16 forming a shoulder 19 therearound. For about half the length of the nipple, from this outer end, the interior passage of the nipple is materially larger 95 than the continuation thereof to the inner end of the nipple, forming an annular valve seat or shoulder 20 inside the nipple. The outer section 21 comprises a body with an outwardly extending hose-nipple 22 and a 100 passage from the outer end of this nipple 22 to the other end of the section, where there is a counter-bore that receives the extension 18 of the nipple 15 snugly, with the inner end of the section 21 fitting closely against the outer shoulder 19 of the nipple 15. The connection-nipple 23 extends up from the top of the outer section 21, with a connec-

tion-head 24 at its top, with a passage down into the passage of the valve-body outer section 21; this passage opening upwardly into a counter-bore 25 in the top of the connection-head 24, which latter is externally threaded.

The movable valve-element is a ball 26 materially less in diameter than the larger part of the passage of the nipple 15, to seat 10 against the shoulder or seat 20; and is held in this part of the passage by upsetting slight opposite parts 27 of the rim of the end of the nipple extension 18 before the valve-body outer section 21 is fitted onto this 15 extension as just described. Then this section is thus fitted on; upon which the extension passage aligns with the passage of the section 21 and becomes practically continuous therewith horizontally. These parts 20 may be held together by the tightness of fit of the nipple extension 18 in the counter-bore of the section 21; or they may be brazed or soldered or otherwise specially fastened together. By any such means, the nipple 15 25 and section 21 thus become unitary, with the valve-ball 26 free to operate inside of them, to close the passage when moved inwardly against the seat 20, but to leave it open when moved outward and stopped by 30 the slight parts 27; and with the upper passage to the connection-nipple open into the valve passage outside the range of the valve element or ball 26.

The head 28 of the pump is an inverted 35 cup with the upper end of the cylinder-shell 7 screwed into its lower end part, but not entirely to the under side of its top 29. On the upper side of this top 29 is the hub 30, centrally thereof, with opposite flat sides 40 31 for engagement in screwing the head 28 onto the cylinder-shell 7. This pump-top 29 has the relatively large tapped opening 32 centrally through it and its hub 30.

The upper inlet-valve comprises the disk 45 33 with a central opening 34, and a washer 35 with a like central opening 36, and with peripheral recesses 37 substantially diametrically opposite on a line substantially at right angles to a radius of the disk and 50 washer on which is located an upstanding handle-element 38, the bottom of which extends through the washer 35 and is fixed, as by riveting or soldering, in the disk 33, about half-way from the central openings 34 and 55 36 out to the peripheries of the disk and washer, and holding these together with the washer 35 close against the upper face of the disk, concentric therewith. This washer may be additionally held by cementing or 60 otherwise fastening to the disk 33. It will thus cover the upper face of the disk, except where it has the recesses or openings 37. The pump-top 28 has, preferably symmetrical to one of the curved sides of the hub 30, and 65 with its inner edge substantially coincident

therewith, a segmental slot 39 a little wider than the handle-element 38; which latter extends up therethrough, with the upper face of the washer 35 adapted to come tight against the under face of the top 29. Close 70 to opposite ends of the slot 39, the curved face of the hub 30 has upright grooves 40 and 41, respectively, adapted to receive the handle element 38 loosely but retentively.

The lower gland 42 comprises a head 43, 75 a short smooth body 44, and a reduced end part 45, externally threaded to screw into the tapped opening 32 of the pump-top 28, with the end of the body 44, which is concentric with the end part 45, forming a 30 shoulder; so that this gland, when its end part 45 is screwed into the lower end part of the opening 32, will bring its shoulder up against the under surface of the top 29, tightly holding the gland in position, into 85 which it is screwed by the aid of radial slots 46 in its head 43. It has a smooth central bore entirely through it from head to upper end; and its smooth body 44 is slightly less in diameter than the central openings 34 90 and 36 of the disk and washer, 33 and 35, respectively, through which it extends, so that the head 43 holds these up, permitting them to move up and down together, 95 slightly, so the washer 35 can press against the under surface of the top 29, as just stated, or drop slightly therefrom. Also, this disk and washer assembly, with its handle-element 38, can turn on the lower gland 42, within the limits of movement of the 100 element 38 in the slot 39; and it can be held at either end of its movement by engagement of the handle-element in one or the other of the grooves 40 and 41, into or out of which the element 38 can spring, due to 105 its own resiliency and that of the disk 33. At opposite sides of the pump-head 28, down through its top 29, are the inlet-holes or ports 47, so positioned, relatively to the slot 39, that when the handle-element 38 is at 110 one end of the slot, as in Fig. 3, the peripheral recesses or openings 37 of the washer 35 are removed a considerable distance from these holes 47, but when the handle-element 38 is at the opposite end of the slot 39, the 115 recesses or openings 37 register with the holes 47, as in Fig. 4. The handle-element 38 is preferably of heavy wire; and its upper part is bent forwardly, forming a small handle 48.

The upper outlet-valve connects through a 120 tapped opening in the wall of the head 28, within the space left above the upper end of the cylinder-shell 7 and the under side of the head-top 29. Its construction is preferably similar to that of the lower outlet valve, before described; comprising the nipple 15, with enlargement 16, gasket 17, extension 18, seat 20 interiorly, and ball 26 125 in the enlargement of its passage, held by 130

the slight parts 27. The outer section 21' differs from the lower-valve outer section 21 in having merely the bore in its inner end, not opening through its outer end, and having the downward passage into the connecting-pipe 49; the inner end of the section 21' having the counter-bore to receive the nipple extension 18 and fit against the nipple shoulder 19, as fully described for the lower outlet valve, previously. These parts may be fastened together as there stated.

The connecting-pipe 49 extends down alongside the pump-cylinder, with its lower end entering the counter-bore 25 of the connection-head 24, with a gasket 50 thereon, and held by a cap-nut 51, around the pipe and screwing down over the external threads of the connection-head 24. These parts are assembled by swinging them sidewise, as is permitted by the nipples 15 turning in their tapped openings in the base-hub 2 and head 28, far enough to permit the pipe 49 to enter the counter-bore 25; with the cap-nut 51 slid up in the pipe 49, out of the way, to be then slid down and screwed in place, when the pipe 49 and connection-nipple 23 have become alined. Any suitable connection-hose 52 can be slipped onto the hose-nipple 22, as usual with pumps of this kind.

The plunger comprises the middle disk 53, flanked by the upwardly and downwardly opening cup-washers 54 and 55, respectively, and the upper and lower disks 56 and 57, respectively, fitting into the respective cup-washers; with the plunger-rod 58 having its lower reduced end part 59 through the disks and washers, and a nut 59 screwed on it therebelow, holding these plunger parts up against the shoulder 60 where the reduced part joins the larger main part of the rod 58. The latter extends up through the gland 42 and the tapped opening 32 of the pump-head 28, with packing 61 around it in the opening 32 above the gland 42; and the upper gland 62 is screwed down into the upper end of this tapped opening 32, compressing the packing around the rod, as is well known in stuffing boxes. The upper end part 63 of the rod, above the gland 62, is reduced, with the transverse handle 64 slipped onto it, between a lower and upper washer, with a nut 65 screwed on the part 63, confining the handle 64 to the rod, as is well known in pumps. A spring 66 (Fig. 1) around the plunger-rod 58, inside the cylinder, above the plunger, cushions the stoppage of the plunger on the up-stroke, as is also well known in pumps.

Pulling up the plunger forces air against the upper valve assembly, pressing the washer 35 to the under face of the top 29, and forces the ball 26 away from its seat; the air thus being forced down through the pipe 49 and out into the hose 52, to whatever the hose leads to. This will happen if the

disk 33 and washer 35 are turned as in Fig. 3, with the recesses 37 out of register with the holes 47. But if turned so these register, as in Fig. 4, the air will escape around the edges of the disk 33 and through the registering recesses and holes; so that there will thus be no pumping action by this end of the pump. Downward pushing of the plunger will always pump; because the lower-valve disk 8 and its washer 11 always tend to seat, by gravity, with the washer closing the holes 14, and the pressure of the air, under the descending plunger, tightens this closure. The air is forced out past the lower valve-ball 26 and directly into the hose 52. When the plunger is pulled up, atmospheric air raises the disk 8 and washer 11, filling the space under the ascending plunger. Similarly, on descent of the plunger, with the upper end of the pump operating, air forces the disk 33 and washer 35 down, in addition to the tendency of these to fall, by gravity. Rendering the upper end of the pump inoperative, *i. e.*, making the pump single-acting instead of double-acting, is useful in a tire-pump, for instance, after the operator has become tired and the pressure in the tire has risen, so that double-action of the pump is unduly irksome, or impossible, for the operator. A simple shifting of the handle 48 as before described, renders the pump either single or double acting, as the operator may require under these conditions, or for any other reason for changing from one to the other mode of operation.

It will be understood that the disks 11 and 35 are of leather or other suitable material usually employed in cups, washers or gaskets, in this kind of pumps. Likewise with the plunger cups, and the gaskets and packing before referred to.

It is highly desirable to bake enamel on these pumps, and to have them as nearly completely assembled as possible when this is done, while not having the leather or similarly composed parts in the pump, to be burned in the baking. Our construction and arrangement is especially adapted to facilitate this; the outlet-valve parts being entirely of metal, except the small gaskets 17, damage to which will be negligible during the baking, and the inlet valve parts being readily inserted, with their combustible washers, after all other assemblage, and enameeling, has been accomplished, except only the screwing of the pump-head 28 onto the top of the shell 7, with the plunger and its rod and handle in place, and the final connection of the pipe 49 with the nipple 23 as before described. The outlet-valve construction may be completed, on the base and head respectively, in the manner hereinbefore described, before enameeling; so that the base 1, cylinder-shell 7, and pump-head 28 may be temporarily assembled, for enameeling, and

then separated for insertion of the inlet-valve and plunger constructions as before described. The lower inlet-valve structure, the disk 8 with its stem, and the washer 11 5 slipped or cemented thereon, can be dropped in from the top of the cylinder-shell 7 and positioned by inserting a long instrument from said top; thus obviating disconnection of the shell 7 from the base 1 for this insertion, after enameling those parts.

10 The opening 32, receiving the lower and upper glands 42 and 62 in its opposite ends, can be threaded uniformly from end to end; thus providing for the support of the upper 15 inlet-valve and for the formation of the stuffing-box around the plunger rod, at one operation.

20 The general construction of the pump is such that the parts may be large, simple and substantial, with a minimum of care required in fitting and assembling, and in 25 maintenance in use. The pump is exemplified as double-acting, with special novel means for alternatively rendering it single- 30 acting; and it will be understood that other novel details, herein set forth, are beneficial either in single or double action of the pump, whether the pump be designed primarily for single action only, or for alternative double 35 action, as herein exemplified.

35 Variations may arise under different conditions; and therefore, while certain constructional details are deemed preferable in connection with our invention, and we have 40 shown and described these rather specifically in elucidating the construction and use of our invention, as is required, we do not wish to be understood as being limited to such precise showing and description, but having thus fully described our invention,

45 What we claim as new and desire to secure by Letters Patent is:

1. In a pump, a cylinder having an inlet opening in one end, a plunger in said cylinder, 45 means for actuating said plunger, an inlet valve at the other end of said cylinder, a rigid inlet-valve element at said one end, having fixed thereon a gasket face with an opening, means supporting said rigid element to move toward said one end to bear thereon with said gasket face across said inlet opening, or to move away from said end, and to move on said end to present its gasket face with the opening of said gasket 50 face out of register or in register with said inlet opening, alternatively, and outlet valves at opposite ends of the cylinder.

2. In a pump, a cylinder having an inlet opening and an access opening in one end, a 55 plunger in said cylinder, means for actuating said plunger, an inlet valve at the other end of said cylinder, a rigid inlet-valve element at said one end, inside said cylinder, having a gasket face with an opening, means 60 supporting said element to move toward said

one end to bear thereon with said gasket face across said inlet opening, or to move away from said end, and to move on said end to present its gasket face with the opening of said gasket face out of register or in 70 register with said inlet opening, alternatively, a handle-element on said inlet-valve element, extending out through and movable along said access opening to move said valve element, and outlet valves at opposite ends 75 of said cylinder.

3. In a pump, a cylinder having a plunger-rod opening, an access opening, and an inlet opening in one end, an inlet valve at the other end of said cylinder, a double-acting 80 plunger in said cylinder, a plunger-rod on said plunger, extending through said plunger-rod opening, outlet valves at opposite ends of said cylinder, an inlet-valve element around said plunger rod, inside said cylinder, having a face with an opening toward 85 said one end of said cylinder, adapted to seat across said inlet opening, glands in opposite ends of said plunger-rod opening, around said plunger rod, packing in said 90 plunger-rod opening between said glands, around said plunger rod, the inner one of said glands having engaging means restricting said inlet-valve element to a limited movement toward and away from said cylinder end and permitting said inlet-valve element to rotate to present its face with the opening of said face out of register or in 95 register with said inlet opening, alternatively, and a handle-element on said inlet-valve element, extending out through said access opening.

4. In a pump, a cylinder having a plunger-rod opening and an inlet opening in one end, a plunger in said cylinder, a plunger 105 rod on said plunger, extending through said plunger-rod opening, an outlet valve for said cylinder, an inlet-valve element around said plunger rod, inside said cylinder, adapted to seat across said inlet opening, glands in opposite ends of said plunger-rod opening, around said plunger rod, and packing in said 110 plunger-rod opening between said glands, around said plunger rod, the inner one of said glands having engaging means restricting said inlet-valve element to a limited movement toward and away from said cylinder end.

5. In a pump, a cylinder having a valve- 115 stem opening and an inlet opening in one end, a plunger, means for actuating said plunger, an outlet valve for said cylinder, an inlet-valve element inside said cylinder, adapted to seat across said inlet opening, a stem on said valve element, extending out 120 through said valve-stem opening, and engaging means on said stem, outside said cylinder end, to engage with said end, restricting said valve element to a limited movement toward and away from said cylinder 125 end.

6. In a pump, a cylinder having a valve- 130 stem opening and an inlet opening in one end, a plunger, means for actuating said plunger, an outlet valve for said cylinder, an inlet-valve element inside said cylinder, adapted to seat across said inlet opening, a stem on said valve element, extending out through said valve-stem opening, and engaging means on said stem, outside said cylinder end, to engage with said end, restricting said valve element to a limited movement toward and away from said cylinder end.

- der end, said valve element being thus adapted to be assembled in said end of said cylinder by insertion from the opposite end of the cylinder.
5. 6. In a pump, a cylinder having an outlet-valve opening, a plunger in said cylinder, means for actuating said plunger, an inlet valve for said cylinder, an outlet-valve nipple secured in said outlet-valve opening and having a reduced outer extension with a shoulder therearound, and having a passage with an internal annular outwardly facing valve seat and having engaging means on its end, less than the circumferential extent of said end, a movable valve-element in said passage, between said seat and said engaging means, restricted by said engaging means to a limited movement toward and away from said seat, and an outer section having a passage and having an enlarged opening around said passage in its inner end, receiving said nipple extension, whereby said section is fixed to said nipple.
- 10 7. In a pump, a cylinder having outlet-valve openings in its side, near respective ends, a double-acting plunger in said cylinder, means for actuating said plunger, inlet valves at opposite ends of said cylinder, outlet-valve nipples secured in the respective outlet-valve openings, each having a reduced outer extension with a shoulder therearound, and having a passage with an annular outwardly facing valve seat and having engaging means on its end, less than the circumferential extent of said end, movable valve elements in the respective passages, between their seats and engaging means, restricted by said engaging means to a limited movement toward or away from the respective seats, outer sections having passages and having enlarged openings around their passages in their inner ends, receiving the respective nipple extensions whereby the sections are fixed on the nipples, a connecting-pipe fixed to one of said outer sections and communicating with its passage, a connection-nipple fixed to the other section and communicating with its passage and receiving the free end of said connecting-pipe, and means fastening said connection-pipe and connection-nipple together.
- 15 20 25
